UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

LINE-SPACING MECHANISM FOR ADDING-MACHINES, TYPE-WRITERS, AND THE LIKE.

1,167,954.

Specification of Letters Patent.

Patented Jan. 11, 1916.

Application filed August 31, 1905. Serial No. 276,542.

To all whom it may concern:

Be it known that I, JESSE G. VINCENT, a citizen of the United States, residing at Detroit, in the county of Wayne and State of Michigan, have invented certain new and useful Improvements in Line-Spacing Mechanism for Adding-Machines, Type-Writers, and the like, of which the following is a specification.

10 My invention has relation to line spacing mechanism used in connection with platens of adding machines, typewriters, and the like, as well as in a combined typewriter and adding machine and in fact in any machine 15 where paper is to be fed one space at a time, which operation is commonly known as "line spacing". However, for the purpose of a clear and definite description of my invention, I have shown it applied to the well 20 known Burroughs adding machine, as substantially described and illustrated in the William S. Burroughs Patents Nos. 504,963 and 505,078, issued on September 12th, 1893, but as above indicated, my invention is not 25 to be limited to use on this particular machine or to this particular type of machine, but that it is capable of use wherever line spacing is employed.

To those familiar with the art it is a well 30 known fact that line spacing mechanisms heretofore employed are unable to prevent over-rotation of the platen caused by high speeds of some operators, with the result that a uniform and even spacing or movement of the platen has been practically impossible heretofore.

My invention is designed to overcome 35 these difficulties and to provide line spacing mechanism whereby such over-rotation of the platen is absolutely prevented, regardless of the different speeds of different operators and the different characters of stroke or touch of such operators.

My invention also has provision for rotating the platen freely by hand in a novel and simple manner.

Other features of advantage and utility of my line spacing mechanism will be apparent from the description hereinafter given.

In the drawings, Figure I is an elevation, partly in section of the rear end of the right-hand side of a Burroughs adding machine, the cap being shown removed from

the feeding mechanism, which is in association with the platen spindle or shaft; Fig. II a front elevation of the right-hand end of the paper carriage shown in Fig. I but with said cap illustrated in its proper position on the feeding mechanism; Fig. III 60 a perspective view of said cap; and Fig. IV a section taken on the line A—B of Fig. II, and Fig. V a detail view of the two hubs 1731 and 1732.

As the construction and mode of operation of a Burroughs adding machine is so well known and as only a portion of such machine is more or less directly concerned with a proper description for an understanding of my invention, only such particular portion of the machine has been illustrated and need be described.

As is well known by those familiar with the operation of a Burroughs adding machine, a shaft 1100 journaled in bearings 166 in the base 1165 of the machine begins to oscillate in a clockwise direction upon the initial movement of the operating handle or main driving shaft of the machine, and in which oscillation its cam plate 1715 80 is moved from the position shown in full lines in Fig. I to the position shown in dotted lines in said figure. The result of this oscillation of the shaft and its cam plate is to rock the lever 1720 from its full 85 line position to its dotted line position indicated in Fig. I. This lever 1720 which is journaled on the stud or pin 1706 supported by the bracket 765, is provided at its forward end with an anti-friction roller 1735 90 held thereto by the stud 1754 and arranged to contact or coöperate with the cam surface upon the upper edge of the cam plate 1715. The rearward end of the lever 1720 passes through an opening in the back 95 plate 1116 of the machine case and is connected at its extreme rearward end by means of the stud 1755 with a vertically movable or sliding bar or connecting link 1713, which is operatively connected by means of 100 the arm 1723 with the rock shaft 1703 in such manner as to oscillate it in an anti-clockwise direction whenever the lever 1720 is rocked or moved from the full line to the dotted line position of Fig. I, that is whenever the connecting link 1713 is depressed 105 and the arms 1723 thereby oscillated to their dotted line positions indicated in Fig. I.

The connecting link 1713½ is provided with suitable bearings arranged on the back plate 1116 of the machine case to permit it to reciprocate vertically. As indicated in Fig. I, the same has a pin and slot connection with a bracket 1714½.

The shaft 1703 carries at its outer right-hand end, Fig. II, a hub or collar 1731 which has a cut-away portion arranged to coöperate with another cut-away portion of a similar hub 1732 secured to the shaft 1703, all as indicated in detail in Fig. V. The result of this construction is to permit of an oscillation of the shaft 1703 greater than that of the hub 1731 for reasons which will be apparent from the description of the mechanism connected with and operated by the hub 1731. To this hub 1731 is secured a double-armed lever 1711 which is spring pressed in an anti-clockwise direction in suitable manner, as by means of the spring 1783, which is fastened at its lower end to the pin 1758 at the rearward end of the lever 1711 and at its upper end to the pin 1760, projecting laterally from the side plate 1717 of the carriage frame. During the anti-clockwise oscillation of shaft 1703, heretofore referred to, the lever 1711 which is under constant tension because of the spring 1783, will be permitted to oscillate in an anti-clockwise direction until its forward arm contacts and is limited by the stop or adjusting screw marked B1755, which is mounted in a bracket 1755 and provided with a lock nut 1736. Thus, the amount of oscillation permitted to the lever 1711 may be regulated by the operator and consequently the amount of throw or movement imparted to the line spacing mechanism 40 through the medium of operating connections hereinafter described, may be varied for obtaining greater or less degrees of movement of the line spacing mechanism and consequently different amounts of line spacing. It will be understood from the foregoing description that the oscillation of the shaft 1703 exceeds that of the lever 1711 and that, when the shaft 1703 starts on its anti-clockwise movement, such lever 1711 will immediately follow and move in unison with such shaft until its forward arm contacts and is stopped by the adjusting screw B1755. The connection of the lever 1711 or rather of its hub 1731, formed separate or integral therewith as desired, is such that the shaft 1703 is moved farther to complete its entire stroke and as such shaft 1703 returns, actuated in a clockwise direction by suitable spring tension, as by means of the spring 1781, it will pick up the lever 1711 where it left it and carry it back to the normal position. It will therefore be understood that the amount of movement of the lever 1711 is directly under the control of the stop B1755, and that the degree of such

movement may be varied, as determined by the operator, inasmuch as such stop is an adjustable one.

The outer or rearward arm of the lever 1711 is pivotally connected by means of the inner end of the spring stud 1758, with the lower end of a link 1710 which is longitudinally slotted intermediate its length so as to receive the other spring pin or stud 1760. The upper end of the link 1710 is pivotally connected to another link 1712, which is itself directly connected with the feeding mechanism, these links forming the operating connection or medium between the lever 1711 and such feeding mechanism, with the result that the oscillations of such lever are imparted to the feeding mechanism and the platen rotated a line space at every oscillation. The pin 1760 not only guides the link 1710 in its described movement, but also acts as a stop in the downward movement of such link so as to determine the extent of such movement and the proper position of the lever 1711 under normal conditions, such position being indicated in full lines in Fig. I. It will be observed that the two links 1710 and 1712 are loosely pivoted at a point in the line of or coincident with the extended axis of pivoting of the carriage, such axis being at the center of the stud 1761, with the result that when the carriage is thrown back to expose the printing line no movement of the feeding mechanism can take place and consequently such movement of the carriage will have no effect upon the feeding mechanism, whereas in other constructions of line spacing mechanism such movement of the carriage causes the usual ratchet wheel to be moved slightly forward in a clockwise direction, with the result that the first line space after the carriage has been thus raised or thrown back is shorter than it should be.

The link 1712 is pivotally connected at its upper end with a plate 1610 loosely pivoted on the platen shaft or spindle 1705, and carrying at its outer end a pawl 1611 which is spring pressed inwardly so as to engage the teeth of a ratchet wheel 1630. The heretofore described oscillations of the lever 1711 are directly imparted to this pawl-carrying plate 1610 and by it transmitted through its pawl to the ratchet wheel 1630.

When the machine is normal, all the parts will be in the position shown in solid lines in Fig. I, but as the operating handle starts forward the parts will gradually move toward the position shown in dotted lines in Fig. I and will come to such dotted-line position shortly before the handle reaches the end of its forward stroke, such result being attained by means of the shape or contour of the cam face of the plate 1754 on the shaft 1100. According to the present and particular construction now being

described the feed pawl 1611 in traveling from the position shown in solid lines to the position shown in dotted lines in Fig. I will move past and engage the fourth tooth on the ratchet wheel, and as the operating handle or main shaft of the machine starts on its return stroke and the feed pawl is gradually moved or oscillated back to its solid-line position, the ratchet wheel will be partially rotated in a clockwise direction through a space equal to four ratchet teeth.

As hereinbefore suggested, there is a great tendency of the platen to travel slightly farther than it is actually moved by the feed pawl, due to rapid speed or quick stroke or touch of some operators, with the result that unequal line spacing is caused. To prevent such over-rotation, I provide locking mechanism which serves to lock the feed pawl to the ratchet upon its return to normal position, that is when the same comes to rest, after having partially rotated the ratchet wheel and the platen shaft to which it is operatively connected. The locking mechanism comprises a stud 1651 rigidly fixed in the right-hand end plate 1719 of the carriage frame, such stud being so located that the feed pawl 1611 will be in contact with it when it comes to rest. It will now be readily seen that when the feed pawl 1611 is resting against and detained by the locking stud 1651, it will be impossible for such pawl to rise out of engagement with the teeth of the ratchet wheel. In other words, the feed pawl 1611 is rigidly locked in engagement with the ratchet wheel and such wheel thereby prevented from any movement other than that which has been actually and properly imparted to it by the feed pawl.

So far as the parts or features already described are concerned, the ratchet wheel may be connected directly with the platen shaft, but as a matter of fact, the same is indirectly connected therewith in such manner that it is possible to move the platen manually in either direction, with the result that the operator is enabled to move or adjust the platen by hand to any desired position. Therefore, in the present instance the ratchet wheel 1630 is loosely mounted upon the platen shaft and recessed in such manner as to form a case or barrel 1630^a serving as a friction ring, the same being slightly greater in diameter than the irregular-shaped disk 1612 arranged therewithin the former constituting the driving member and the latter the driven member. This disk is, in the present instance, three-armed forming marginal recesses and is rigidly secured or fixed to the platen shaft in suitable manner. Between the adjacent arms of the disk are formed two angles at the lower inner corners of the arms and exactly opposed to each other. Between the adja-

cent arms are arranged pairs of rollers 1764 and 1764^{1/2} whose members alternate and which are spring pressed by means of springs 1784 toward the highest points of their respective angles with which they cooperate, with the result that such rollers are forced into close contact with both the disk 1612 and the barrel of the ratchet wheel, thereby forming a strong frictional connection, so that when the ratchet wheel and its barrel are oscillated in the manner already described the movement will be communicated to the disk 1612 and the platen shaft without any lost motion or play whatsoever.

A single set of the rollers, directly opposed to each other, would be sufficient to accomplish the desired end, but in order to create no unnecessary friction and to prevent strain on the shaft carrying the platen, I prefer to provide the three sets of pairs of these rollers as illustrated and just described and to evenly distribute them in a circle around the disk so that all the parts will be balanced.

It will be understood that when the ratchet wheel is moved or oscillated in a clockwise direction, Fig. I, by means of the feed pawl, the three rollers 1764^{1/2} have a tendency to roll out of their angles on the disk 1612, but as there is no "give" to either the disk 1612 or the barrel of the ratchet wheel, such rollers form a driving connection between such disk and barrel and the disk is thereby partially rotated or moved through the same arc that the ratchet wheel is caused to travel.

When the parts come to the position indicated in solid lines in Fig. I, there is a tendency for the heavy platen 1797 to travel slightly farther on account of its momentum, due to causes already stated, but as the ratchet wheel is rigidly locked through the medium of the feed pawl and its locking stud 1651, it will be evident that further rotation of the ratchet wheel is impossible, and in case the platen 1797 should attempt to travel farther, it will, of course, simply exert a force in a clockwise direction on the disk 1612, but as such disk attempts to rotate in a clockwise direction the opposing rollers 1764 being spring pressed into their respective opposite angles, form a solid lock and absolutely prevent any movement of the disk independently of the ratchet wheel. It is evident, therefore, that so long as the rollers 1764 and 1764^{1/2} are operative the ratchet wheel is rigidly and automatically locked to the platen shaft and that they will both have to move exactly at the same time and exactly the same amount, but in order to enable the operator to turn the platen easily by hand to any desired position, I have provided suitable means which in effect renders such rollers inoperative, with the result that the platen shaft, as well as its disk 1612,

may be moved freely in either direction independently of the ratchet wheel and its barrel. To this end, I have provided a plate 1747, which is loosely mounted on the platen shaft and carries three studs 1743 equi-distantly spaced and in such relative position or location that when the parts are assembled, as shown in Fig. II, such studs take the position shown in section in Fig. IV. This plate 1747 is provided with a hub, which carries at its outer end a knurled knob 1795. The plate 1747 which, as stated, is loosely mounted on the platen shaft performs no function during the ordinary operation of the machine further than closing the outer or open end of the barrel of the ratchet wheel. When, however, the operator desires to rotate the platen any desired amount the knurled knob 1795 is simply turned in one direction or the other, with the result that the pins 1743, by reason of their engagement with three corresponding rollers of the sets of rollers, renders the same inoperative and thereby breaks the friction connection between the disk 1612 and the ratchet wheel 1630. For instance, if the operator wishes to turn the plate in a clockwise direction, Fig. I, he simply turns the knob and plate 1747 in that direction, which movement likewise oscillates the pins 1743 in the same direction, with the result that such pins engage the rollers 1764, which of course permits the disk 1612 to move in a clockwise direction without affecting or moving the ratchet wheel. If the operator wishes to rotate the platen in an anti-clockwise direction, he simply turns the knurled knob 1735 in an anti-clockwise direction causing the pins to engage the other rollers 1764₁, whereupon the reverse action will take place.

It will be understood that the plate 1747 can be slightly oscillated in either direction at any time without interfering with the rollers 1764 and 1764₁ as the pins 1743 do not occupy all the space between such rollers. This particular construction is preferable and desirable in order that plenty of room may be had for play between such rollers, so that the pins 1743 will not in any way interfere with the action of the rollers in the ordinary operation of the machine and not unless the knob 1795 is positively moved by the operator.

By the use of my invention all possibility of overthrow of the platen is prevented, and moreover, means are provided for obtaining an independent movement of the platen without interfering with the ratchet wheel. Moreover, my construction is such that it is impossible to move or place the ratchet wheel in such position as by throwing the carriage back that full and proper line space is not obtained and at every operation of the machine, in other words, the bodily move-

ment or shifting of the carriage, together with the ratchet wheel has no effect whatsoever upon the amount of the line space immediately after such carriage has been restored to normal position.

I claim:

1. The combination of a roller platen, a ratchet wheel loosely mounted concentric therewith and having an annular flange, a disk secured to the platen within said flange and peripherally notched angularly, a roller in the notch, and a knob concentric with the platen and having a pin to engage said roller, said knob rotatable to disable the latter and then turn the platen independently of the ratchet wheel. 75 80

2. The combination of a roller platen, a ratchet wheel loosely mounted concentric therewith and having an annular flange, a disk secured to the platen within said flange and having a series of peripheral recesses, the bottoms of which are cammed in opposite directions from an intermediate point, a pair of rollers in each notch and a knob having a pin projecting between the rollers of each pair, said knob rotatable to disable either roller and turn the platen independently of the ratchet wheel. 85 90

3. In line spacing mechanism for adding machines, typewriting machines, and the like, the combination with the rotatable platen and its shaft, a ratchet wheel loosely mounted on the platen shaft and a swinging pawl; of a friction clutch device comprising a clutch ring on the ratchet wheel, a disk connected with the platen and having a marginal recess with two opposing angles, separate rollers in the angles respectively, means for normally pressing the rollers to engaging position, one roller making clutching engagement between said ring and disk in the line spacing operation and the other roller making clutching engagement between said members to lock the platen against independent forward rotation, and a movable disk loosely mounted on the platen shaft and closing the open end of the clutch ring, said disk being provided with an inwardly directed pin normally positioned between said rollers and arranged to be moved to engage either one of said rollers according to the direction of movement of said disk. 115

4. In line spacing mechanism for adding machines, typewriting machines, and the like, the combination with the rotatable platen and its shaft, a ratchet wheel loosely mounted on the platen shaft, and a swinging pawl; of a friction clutch device comprising a clutch ring on the ratchet wheel, a disk connected with the platen and having a plurality of arms with a pair of opposing angles between adjacent arms, series of rollers in the angles respectively, one series transmitting the movement of the 120

ratchet wheel to the disk and platen and the other series locking the platen against independent forward rotation, and a series of pins arranged to be simultaneously moved 5 to engage the rollers of one or the other series according to the direction of movement.

5. In line spacing mechanism for adding machines, typewriting machines, and the 10 like, the combination with the rotatable platen and its shaft, a ratchet wheel loosely mounted on the platen shaft, and a swing- 15 ing pawl; of a friction clutch device comprising a clutch ring on the ratchet wheel, a disk connected with the platen and having a plurality of arms with a pair of opposing angles between adjacent arms, series of rollers in the angles respectively, one series transmitting the movement of the ratchet 20 wheel to the disk and platen and the other series locking the platen against independent forward rotation, and a disk provided with a series of laterally projecting pins 25 normally positioned between the rollers and adapted to engage the rollers of one or the other series according to the direction of movement.

6. A rotatable platen, line spacing mechanism for rotating the same comprising a 30 ratchet wheel connected therewith, a swinging pawl coöperating with the ratchet wheel to move the same for each line space, a carrier which is mounted to swing on the platen shaft and on which the pawl is pivoted, a 35 rocking lever, and a pair of links pivoted to each other and pivoted respectively to the pawl carrier and to the rocking lever.

7. A rotatable platen, line spacing mechanism for rotating the same comprising a 40 ratchet wheel connected therewith, a swinging pawl coöperating with the ratchet wheel to move the same for each line space, a carrier which is mounted to swing on the platen shaft and on which the pawl is pivoted, a 45 rocking lever, means for adjusting the degree of movement of such lever, operating connections between the lever and pawl carrier, and means for vibrating said lever with provisions for lost motion.

50 8. A rotatable platen, line spacing mechanism for rotating the same comprising a ratchet wheel connected therewith, a swinging pawl coöperating with the ratchet wheel to move the same for each line space, a carrier which is mounted to swing on the platen 55 shaft and on which the pawl is pivoted, a rocking lever and operatively connected with the pawl carrier, a spring-held rock shaft having a one-way driving engagement 60 with said lever, and a reciprocating bar operatively engaged with said rock shaft.

9. A rotatable platen, line spacing mechanism for rotating the same comprising a

ratchet wheel connected therewith, a swinging pawl coöperating with the ratchet wheel 65 to move the same for each line space, a carrier which is mounted to swing on the platen shaft and on which the pawl is pivoted, a rocking lever operatively connected with the pawl carrier, a rock shaft for actuating such lever, a reciprocating link or bar operatively connected with the rock shaft, a cam 1715, and an operating connection between the cam and the reciprocating link. 70 75

10. A rotatable platen, line spacing mechanism for rotating the same comprising a ratchet wheel connected therewith, a swinging pawl coöperating with the ratchet wheel to move the same for each line space, a carrier which is mounted to swing on the platen shaft and on which the pawl is pivoted, a 80 rocking lever operatively connected with the pawl carrier, a rock shaft for actuating such lever, a reciprocating link or bar operatively connected with the rock shaft, a cam 1715, and an operating connection between the cam and the reciprocating link, comprising a rocking lever 1720 pivotally connected at one end to such link and having at its other end a roller coöperating 85 90 with said cam.

11. The combination with the platen frame and rotatable platen and also the carriage to which the platen frame is pivoted, 95 of line spacing mechanism comprising a ratchet wheel loosely mounted on the platen shaft, a friction clutch connection between such wheel and the platen shaft, a pawl coöperating with the ratchet wheel, a pawl carrier on which the pawl is mounted, and a pair of links, one of which is operatively connected with the pawl carrier and the other arranged to be operated by a movable part of the machine to which the paper carriage is applied, said links being pivoted to each other at a point coincident with the axis of pivoting of the platen frame to its carriage. 100 105

12. In combination with a platen having 110 a ratchet wheel for driving the same, of an arm, a pawl, carried thereby, a lever, for oscillating the said arm, and a pair of links connecting the lever to the arm-carrying pawl for operating the latter. 115

13. In combination with a platen a ratchet concentric therewith, an arm, a pawl carried by the arm and engaging the ratchet, a lever, for operating the arm, a slotted link, a pin engaging the slot in the link, 120 and a link connecting the link and the pawl-carrying arm.

JESSE G. VINCENT.
